P. PLANTINGA,
SHAPER AND THE LIKE.
APPLICATION FILED JAN. 24, 1917.

Patented Aug. 6, 1918.

UNITED STATES PATENT OFFICE.

PETER PLANTINGA, OF ROCHESTER, NEW YORK, ASSIGNOR TO DAVIS MACHINE TOOL CO., INC., OF ROCHESTER, NEW YORK, A CORPORATION OF NEW YORK.

SHAPER AND THE LIKE.

1,274,771.

Specification of Letters Patent.

Patented Aug. 6, 1918.

Application filed January 24, 1917. Serial No. 144,275.

To all whom it may concern:

Be it known that I, PETER PLANTINGA, of Rochester, in the county of Monroe and State of New York, have invented certain new and useful Improvements in Shapers and the like; and I do hereby declare the following to be a full, clear, and exact description of the same, reference being had to the accompanying drawings, forming a part of this specification, and to the reference characters marked thereon.

My invention relates to improvements in shapers and the like and has for its object to provide more particularly means for readily adjusting the stroke of shaper rams or tool slides of other metal cutting machines, so that the path of travel of the ram or slide may be shifted either forwardly or backwardly as desired according to the nature of the work to be performed. A further object of the invention is to provide means for quickly and positively locking the ram adjusting mechanism at whatever points it is desired to hold the same. To these and other ends the invention consists in certain improvements and combinations of parts, all as will be hereinafter more fully described, the novel features being pointed out in the claims at the end of the specification.

30 In the drawings:

Figure 1 is a side elevation partly in section of a machine embodying one form of the invention;

Fig. 2 is an enlarged detail section taken 35 on line *a--a* of Fig. 1;

Fig. 3 is an enlarged transverse sectional view taken on line *b--b* of Fig. 1;

Fig. 4 is an enlarged plan section taken 40 on line *c--c* of Fig. 1.

Similar reference characters throughout the several views indicate the same parts.

My invention comprises an improved ram adjusting mechanism together with locking means therefor, the former operating to effect quick and positive adjustment of the ram relatively to the work piece and the latter constituting means for safely locking the adjusting mechanism in whatever position it is desired to hold the same. The mechanism is preferably designed for adjusting the rams of machines known as shapers, but is readily applicable to other types of metal cutting machines. Referring to the drawings by numerals, 10 represents 45 the frame or supporting column of the ma-

chine upon which is carried any approved form of work support such as that indicated at 11 for holding the work piece 12 which, in the present instance, comprises a shaft upon which it is desired to form a longitudinal cut or key slot as shown. The V-shaped ram 13 is slidably mounted upon suitable guides formed at the top of the column as shown in Figs. 1 and 3. The tool 14 is carried on an adjustable head 15 at the forward end of the ram. Mounted within the ram is a slide block 16 to which is pivotally connected at 17 the rocker arm 18, the lower end of which slides in the socket formed in the shoe 19 which has a rocking motion on a shaft passing through the column. The top of the rocker arm 18 is so constructed that the long shaft 12 forming the work piece may be passed therethrough without interfering with the operation of the arm.

The driving mechanism for the ram comprises the pinion 20 meshing with the gear 21 carrying the crank 22 and slide block 23 for rocking the arm or slotted lever 18 50 whereby movement of the slide 16 is effected to reciprocate the ram 13.

The adjusting mechanism for the ram comprises the transverse threaded block 24 with which is connected the feed screw 25, 55 the front of the screw having a journal 26 rotatable in a bearing 27 formed upon the back of the slide block 16 as shown in Fig. 1. The slide block has a recess 28 formed at its center to receive the intermeshing beveled gears 29 and 30, the former being rigidly connected with an extension 31 upon the journal 26 and the latter rigidly connected with a vertical shaft 32, the lower end of which is preferably seated in a cavity 95 formed in the bottom wall of the slide block while the upper end extends through the slide block and ram to receive the operating handle 33, which is keyed or otherwise rigidly connected with said shaft.

Means for clamping the slide block upon the ram comprises the sleeve or quill 34 and the lever 35 for rotating the same, the sleeve extending through the top wall of the slide block in threaded engagement therewith, while the slide block is provided with guides 36 slidably mounted upon the guideways 37 formed upon the ram as shown in Fig. 3, it being understood that movement of the lever 35 in one direction will tighten the slide 100 110

block upon the ram and movement of said lever in an opposite direction will loosen the same. The hand wheel 33 is rotatably mounted upon the top of the sleeve 34 so that rotation of said wheel will not effect rotation of the sleeve. Accidental removal of the hand wheel 33 from the sleeve is prevented by the reduced end of a set screw 38 extending into a groove 39 formed exteriorly of the top of the sleeve as shown in Fig. 3. The sleeve is also provided with a collar 40, the upper side of which forms a seat for the hand wheel and the lower side acting to prevent upward movement of the lever 35.

In order to provide a positive locking means for the slide block 16 I have rigidly connected preferably with the beveled gear 30 a gear wheel 40, the teeth of which are adapted to normally receive the locking projection 41 on the bottom of the plunger head 42 actuated by the spring 43 in the cavity 44 formed in the front wall of the slide block 16. Rigidly connected with the lower extremity of the sleeve 34 is a cam 45 positioned opposite the upper portion of the plunger head 42 and movable by operation of the lever 35 to actuate the plunger outwardly until the locking projection 41 disengages the teeth of the gear 40 so that the hand wheel 33 and shaft 32 may be rotated to operate the feed screw 25 for adjusting the ram 12.

The feed screw block 24 is provided at its upper side with a projection 46 extending upwardly between and in sliding engagement with the guides 47 formed upon the ram as shown in Fig. 2. The block 24 is connected with the upper wall of the ram by the machine screws 48, the heads of which fit loosely in the cavities 49 formed in the ram so that a slight up and down movement of the block is permitted. In order to prevent rocking or shifting of the block by the action of the feed screw I have rigidly connected therewith a pin 50 which is snugly fitted in an aperture formed in the upper wall of the ram, the pin being free to slide up and down in the aperture while being prevented from moving laterally therein. In the operation of the ram adjusting mechanism movement of the ram either forwardly or backwardly is effected by turning the hand wheel 33 to rotate the beveled gears 30 and 29, the latter operating the feed screw 25 upon the block 24 to adjust the ram so that it may be brought into position to cause the tool to engage the work piece at whatever point it is desired to operate upon the same. When the ram has been properly adjusted the lever 35 is moved to operate the sleeve 34 for rotating the cam to release position at which time the locking projection 41 on the plunger 42 will be moved by the spring 43 into locking engage-

ment with the teeth of the gear 40 as shown in Fig. 4. With the parts in this position the slide block 16 is positively locked upon the ram and release of the block is made dependent upon movement of the lever by the operator. Operation of the lever to rotate the cam for the purpose of releasing the plunger 42 to lock the gear 40 will at the same time cause the ribs 36 of the slide block 16 to be drawn into clamping engagement with the guides 37 of the ram as shown in Fig. 3. It will thus be seen that both the clamping and locking mechanisms for the slide block are simultaneously operated by movement of the lever 35 and sleeve 34, the clamping of the slide block upon the ram serving to provide a rigid connection for the rocker arm while the latter is in operation and the gear 40 and plunger projection 41 a positive locking means to prevent accidental displacement of the operating sleeve 34 while the ram is being reciprocated upon the frame or bed of the shaper.

I claim as my invention:

1. In a shaping machine, the combination with a reciprocally mounted ram, a slide block thereon, a screw rotatably mounted in the slide block and operatively connected with the ram, means supported in the slide block for actuating the screw for effecting a relative adjustment between the slide block and ram, and means for reciprocating the slide block.

2. In a shaping machine, the combination with a reciprocally mounted ram, a tool head mounted thereon, a slide block also mounted thereon, a screw rotatably mounted in the slide block and operatively connected with the ram, a manually operated shaft also mounted in the slide block, means operatively connecting said shaft and said screw, and means for reciprocating the slide block.

3. In a shaping machine, the combination with a reciprocally mounted ram, a tool head mounted thereon, a slide block also mounted thereon, a screw rotatably mounted in the slide block and operatively connected with the ram, a manually operated shaft also mounted in the slide block, means operatively connecting said shaft and said screw, means for clamping said slide block to the ram, and means for reciprocating the slide block.

4. In a shaping machine, the combination with a reciprocally mounted ram, a tool head mounted thereon, a slide block also mounted thereon, means for adjusting said block and said ram relatively to each other, means for locking said adjusting means, and means for operating said locking means and simultaneously clamping the block to the ram.

5. A shaping machine comprising a ram, a clamping block thereon, means for shifting one relatively to the other, means for clamp-

ing the block upon the ram, a plunger arranged to be moved into locking engagement with said shifting means upon operation of the clamping means to tighten the block 5 upon the ram and a cam for moving the plunger out of locking engagement.

6. A shaping machine comprising a ram, a clamping block thereon, means upon the clamping block for shifting the same relatively to the ram, means for clamping the block upon the ram, a member arranged to be moved into locking engagement with said shifting means upon operation of the clamping means to tighten the block upon the ram 10 and means for actuating the block to effect operation of the ram.

7. A shaping machine comprising a ram, a block thereon, means upon the block connected with the ram for shifting the latter 20 relatively to said block, a toothed member carried by the last mentioned means, a locking member movable into and out of engagement with said toothed member, means for clamping said block to the ram, a member 25 carried by the clamping means for moving the locking member out of engagement with said toothed member when the block is loosened upon the ram and means for moving said locking member into engagement 30 with the toothed member when the block is tightened upon the ram.

8. A shaping machine comprising a ram, a block thereon, means connecting the block and ram operable to effect adjustment of the ram relatively to the block when the latter is loosened upon the ram, a sleeve having 35 threaded engagement with the block, means for rotating the sleeve to clamp the block upon the ram and a shaft extending through 40 the sleeve operatively connected with the ram adjusting means.

9. A shaping machine comprising a ram, an adjusting block thereon, a sleeve connected with and movable upon the block, a 45 shaft extending through the sleeve, means controlled by the shaft for effecting movement of the ram relatively to the block, means for locking the shaft against rotation, and means connected with the sleeve for effecting the release of said locking means.

10. A shaping machine comprising a ram,

an adjusting block thereon, a rotatable sleeve connected with and movable within the block, a shaft extending through the sleeve, means controlled by the shaft for effecting 55 movement of the ram relatively to the block, a spring pressed plunger for locking the shaft against rotation, a cam connected with the sleeve operable to effect release of the plunger and means for effecting rotation of 60 the sleeve.

11. A shaping machine comprising a ram, an adjustable block therefor, means for moving the block to tighten and loosen the same upon the ram, a feed screw connected 65 with the block and movable therewith when the latter is adjusted into and out of clamping engagement with the ram, a member loosely mounted upon the ram arranged to effect movement of the latter and adapted 70 to threadedly engage the feed screw, means for turning the feed screw to cause the ram to move relatively to the block and means for reciprocating the block to effect reciprocation of said ram.

12. A shaping machine comprising a ram, an adjustable block therefor, means for moving the block to tighten and loosen the same upon the ram, a feed screw connected with the block and movable therewith when the 80 latter is adjusted into and out of clamping engagement with the ram, a block mounted on the ram threadedly engaging the feed screw, the said block being movable upon the ram in a direction at an angle to the longitudinal axis of the feed screw and means for reciprocating the block to effect reciprocation of the ram.

13. In a shaping machine, the combination with a ram, a block mounted thereon, a 90 sleeve mounted to turn in the block for clamping the block to the ram, and a shaft revolubly mounted in the sleeve for moving the block and ram relatively to each other.

14. In a shaping machine, the combination 95 with a ram, a block mounted thereon, a sleeve mounted to turn in the block, a shaft revolubly mounted in the sleeve for moving the block and ram relatively to each other, and means controlled by said sleeve for locking said shaft against movement.

PETER PLANTINGA.
